Primary Examiner—Cynthia E. Ramirez

(57) **CLAIM**

The ornamental design for a packaging carrier consisting of loading ledges and platform, as shown.

DESCRIPTION

FIG. 1 is a top perspective view of the packaging carrier consisting of loading ledges and platform showing my new design;

FIG. 2 is a bottom perspective view thereof;

FIG. 3 is a top perspective view of the platform;

FIG. 4 is a bottom perspective view of the platform;

FIG. 5 is a plan view of an unfolded blank of the platform thereof;

FIG. 6 is a top perspective view showing an alternate embodiment from the one shown in FIG. 3;

FIG. 7 is a bottom perspective view thereof; and,

FIG. 8 is a plan view of an unfolded blank of the platform shown in FIG. 6.

The loading ledges are not shown in FIGS. 3 through 8 for convenience of illustration.

The broken lines in FIGS. 5 and 8 depict creases.
